FRENCH E. DENNISON, OF BELOIT, WISCONSIN, ASSIGNOR TO NATIONAL REFRIGERATION CORPORATION, OF BELOIT, WISCONSIN, A CORPORATION OF DELAWARE

REFRIGERATING APPARATUS

Application filed July 22, 1926. Serial No. 124,125.

This invention relates to refrigerating machines of the type wherein the refrigerating medium is compressed, after which such medium is led through condensing means, discharged therefrom into a receiver and subsequently allowed to circulate through expansion means from which it is returned to the compressor.

Machines of the above type are usually used under conditions where compactness is essential. It has been customary in the past to construct such machines with the receiver for the refrigerating medium separate from the compressor and condensing means. This was due principally to the difficulty in constructing such containers compactly with the said compressor and condensing means because of the care required of these parts and the consequent need of accessibility thereto, and to other reasons.

Some machines of the above type have been used in the past in which the receiver for the refrigerating medium has been disposed in proximity to the rest of the machine for the sake of space economy but in such cases the arrangement of such receivers relative to the compartment containing the condensing means has not been such as to permit heat transference between the receiver and the condensing chamber or compartment or the crank case of the compressor.

It is accordingly the principal object of this invention to provide a more efficient machine which will overcome the above mentioned difficulties.

It is more particularly an object of this invention to provide a machine in which the receiver is mounted adjacent the compressor and condensing chamber in such a manner as to provide a maximum of heat transference between the compressor, condensing chamber, receiver for said refrigerant, and the surrounding atmosphere. The construction at the same time affording both space economy and an ample amount of accessibility to the various parts.

It is also an object of this invention to provide such a machine in which the receiver is compactly arranged with respect to the compressor and the condensing means without

the necessity of disposing the container in the base of the machine which would not only increase the size and height of the base but also necessitate a base of special construction.

Other and further objects of this invention will be apparent from the specification and claims when taken in connection with the accompanying drawings wherein,

Fig. 1 is a longitudinal elevation partly in section and with parts removed showing an ice machine of this invention;

Fig. 2 is a transverse section taken at the line 2—2 of Fig. 1 and showing parts in elevation.

Referring to the drawings more particularly, numeral 1 represents the base of the machine of any preferred construction preferably carried by legs 2. The base is cast separately from the other parts which are mounted thereon. On one end of the base 1 is bolted a casting 3 which forms a bell shaped chamber 4 constituting the crank case of the compressor and also a chamber 5 partially surrounding the crank case and serving as the receiver for the condensed refrigerant. The chamber 5 does not extend completely around the crank case 4, but the ends of said chamber terminate adjacent an annular shoulder 6 at one side of the crank case 4. The shoulder 6 surrounds an opening 7 in one side of the crank case for receiving a driving shaft 8 provided with a crank 9 thereon within the crank case 4. The side of the crank case 4 opposite to the opening 7 is cast with a hollow boss 10 extending outwardly of said case into the chamber 5, and adapted to receive the bearing bushing 11 for one end of the crank shaft.

A disk 12 is secured on the shoulder 6 for closing the opening 7 and is provided with opposite bosses 13 and 14 on its outer and inner faces respectively. The shaft 8 extends through the bosses 13 and 14 and bears on a bushing 15 secured within the boss 14. The boss 13 is cored out to receive a stuffing box 16, said stuffing box including a threaded member 17 on said boss 13. The outer end of the shaft 8 is fastened to a driving wheel 18 which also acts as a fly wheel. The wheel 18 is driven through a belt 19 from a motor

20 mounted at the other end of the base 1. An oil pipe 19' threaded in the upper side of the plate 12 communicates with suitable passages therein for delivering oil to the interior of the crank case 4.

5 The upper end of the crank case 4 merges into a cylindrical guide 20 in which is slidably contained a piston cross head 21 operatively connected through a connecting rod 22 to the crank 9. Surrounding the upper 10 end of the cylinder 20 and concentric with the said cylinder is an annular groove 23 the purpose of which will be apparent herein-after. The outer edge of the groove 23 provides a shoulder 24 on which is secured a hollow cylindrical member 25, the lower end of which is slightly enlarged and provided with an integral flange 26 which is bolted to said shoulder. The cylinder 25 is aligned 15 with the cylinder 20 and slidably contains a compressor piston 27 connected through a rod 28 to the cross head 21. A closure 29 is provided on the upper end of the cylinder 20, said closure having a suitable stuffing box 25 and opening therein for the rod 28. The piston 27 is provided with the usual suction valve 30 and a discharge valve 31 is mounted over the upper end of the cylinder. The upper end of the cylindrical member 25 is provided with a flange 32 on which rests a ring 33 carrying a plate 34. The plate 34 and ring 33 are secured to the flange 32 by means of bolts 35 which extend through said ring into said flange.

35 A condensing coil 36 surrounding the cylindrical member 25 is connected at one end to chamber 37 formed within the ring 33 as indicated at 65. The lower end of the coil is connected in a suitable manner to a passage 38 in the casting 3. The passage 38 extends outwardly in a shoulder 39 on the casting 3 and communicates with a fitting 40 having a high pressure cut-out 41 connected thereto. The cut-out 41 contains a pressure 45 operated switch which is adapted to shut off the motor 20 when the maximum pressure is reached and turn the machine on again when the pressure is again normal. A separate passage 42 is provided in the casting 3 50 through the shoulder 39 spaced from the passage 38 and communicating with the receiver 5. Communication is established between passages 38 and 42 through a passage 44 in the fitting which is equipped with a shut off 55 valve 43 which may be closed when repairs to the machine are necessary.

The lower end of the crank case 4 is provided with an opening 45 and a plate closure 46 for said opening which may be removed to 60 permit access to the interior of the crank case. A suitable drain plug 47 is threaded in the plate 46.

The upper end of the casting 3 is provided with an annular shoulder 48 on which is secured a shell 49, the latter enclosing the up-

per end of the compressor and the condensing chamber. The shell 49 is connected at its lower end with a cooling water supply pipe 50 for admitting cool water to the chamber formed within said shell and is provided at its upper end with a delivery pipe 62.

70 The base 1 is cut away to permit access to the bottom of the crank case 4 through the plate 46. The lower portion of the chamber 5 is provided with a connection 53 to the expansion coils (not shown).

75 Means are provided for controlling the admission of cooling water through the pipe 50 to the condensing chamber within the shell 49. Such means includes a control valve 54, the stem 55 of which is actuated by a bell crank lever 56, one arm of which extends upwardly and is provided with an adjustable member 57 substantially in alignment with the shaft 8 and carrying a ball member 58 at 80 one end thereof. A centrifugal governor 59 operatively mounted on the wheel 18 operates through a slideable sleeve 60 upon the ball 58 to swing the lever 56 in accordance with the speed of the compressor thereby 85 controlling the valve 54. When the compressor is idle the valve is entirely shut off thereby conserving water. A connection 61 at the bottom of the groove 23 communicates with the other end of the expansion coils.

90 The compressor on being driven through the motor 20 causes the gas comprising the refrigerant to be forced above the piston 27 on the down stroke thereof, the valve 30 therein opening during said stroke. Upon the upward stroke of the piston 27, the gas will be compressed and discharged through the valve 31 into the coils 36 where it is cooled by the water within the shell 49 and is discharged in condensed form through the passage 38 and 42 to the chamber 5. The chamber 5 acts as the receiver for the condensed refrigerant from which it is delivered through the connection 53 to the expansion coils where it expands and is then returned from the low side through the connection 61 to the groove 23 at the base of the compressing cylinder.

95 It will be observed that the casting mounted upon the base is shaped to form both the crank case 4 and the receiver 5 immediately surrounding or partially surrounding the crank case and that the receiver and crank case have a common dividing wall which readily permits heat transference therethrough. This prevents heating of the crank bearing since the heat generated in the crank case is conducted through the oil and said wall to the receiver thereby maintaining the crank case and its contents at a moderately low and 100 efficient temperature.

105 It will be further observed that the upper wall of the casting forms a common dividing wall between the cooling chamber and the receiver so that the receiver is cooled from 110

the water in the cooling chamber. This construction further promotes economy and efficiency of the machine and in addition a maximum area of the receiver is exposed to the surrounding atmosphere so that it is cooled to a considerable extent thereby.

The casting is further formed to provide the two legs 38 and 42 of the passage which conducts the condensing refrigerant to the receiver and the fitting 40 attached to the casting and establishing communication between the legs 38 and 42 of the passage contributes toward economy in construction. The shut off valve carried by this fitting is in accessible position where it may be readily closed when ever access to the compression cylinder or other parts of the system are required thereby closing off the receiver so as to preclude the escape of the refrigerant therefrom.

The whole assembly is extremely compact in its arrangement so that it occupies a minimum of space. The crank case receiver and cooling chamber are disposed so as to permit the ready transference of heat units from one to the other. The receiver presents a maximum of exposed surface to the cooling effect of the surrounding atmosphere and the structure as a whole is capable of being very economically manufactured and is highly efficient and durable in use.

I am aware that many changes may be made and many details of construction varied without departing from the principles of this invention and I do not propose being limited otherwise than necessitated by the prior art.

I claim:

1. A refrigerating machine comprising a compressor including a compression cylinder and a crank case, a receiver for liquid refrigerant formed integrally with and partially surrounding said crank case, a cooling chamber surrounding the compression cylinder immediately above said receiver, condensing coils arranged in the cooling chamber and connected at opposite ends to said compressor and to said receiver, and means for actuating said compressor.

2. A refrigerating machine comprising a casing shaped to provide a crank case and a receiver for liquid refrigerant partially surrounding the same, a compression cylinder mounted upon said casing, condensing coils surrounding the cylinder and connected at opposite ends to said cylinder and receiver, and a hood inclosing said coils and cylinder and forming a cooling chamber immediately above said receiver.

3. A refrigerating machine comprising a casting shaped to provide a crank case, a compression cylinder mounted on said casting, a condensing coil surrounding the cylinder, a cooling chamber in which said coil is disposed, a connection between said coil and

said receiver including a receiver, a passage formed partially in said casting and partially in a fitting attached to the casting, a valve for closing said passage, and means for supplying a cooling fluid to said chamber.

4. A refrigerating machine comprising a casing providing a crank case, a passage for the refrigerant, and a receiver for liquid refrigerant substantially surrounding the crank case, a compression cylinder mounted upon the casing, a condensing coil surrounding the cylinder and connected with said passage and cylinder, and a hood inclosing said coil and cylinder and forming a chamber for a cooling fluid, said passage connecting said coil and said receiver.

5. A refrigerating machine comprising a casing providing a central crank case substantially surrounded by a receiver for liquid refrigerant, the crank case and receiver having a common wall permitting heat transference from the crank case to the receiver, a compression cylinder mounted on the casing, and a hood mounted on said casing and surrounding the cylinder to form a cooling chamber around the cylinder, the upper wall of the casing forming a common wall between the cooling chamber and the receiver permitting heat transference therethrough.

6. A refrigerating machine comprising a receiver for liquid refrigerant, a crank case partially surrounded by the receiver, said crank case and receiver having a common wall permitting heat transference therethrough, and a cooling chamber above the receiver, said cooling chamber and receiver having a common wall permitting heat transference therethrough.

7. A refrigerating machine including a casing forming a crank case and a receiver having a common wall therebetween, a hood mounted upon said casing and forming a cooling chamber, the top of said casing forming a common wall between the receiver and the cooling chamber, a compression cylinder mounted on said casing, a condensing coil surrounding said cylinder within said cooling chamber, and a connection between said coil and said receiver including a passage formed in said casing.

8. A refrigerating machine comprising a compressor including a compression cylinder and a crank case, a cooling chamber having a refrigerant condensing coil therein connected to the cylinder surrounding the compression cylinder, and a liquid refrigerant receiver connected to said coil substantially surrounding and integral with said crank case the receiver having its sealing wall in common with substantially the entire bottom of said cooling chamber.

9. A refrigerating machine comprising a compressor including a compression cylinder and a crank casing, a cooling chamber sur-

rounding the compression cylinder, and a receiver substantially surrounding said crank case, receiver and crank case being integral.

10. In a refrigerating machine, a vertically extending compression cylinder and a crank case at the lower end thereof, a cooling chamber above the crank case surrounding the compression cylinder and having a coil therein connected to the cylinder for cooling a refrigerant, and a liquid refrigerant receiver underneath said chamber substantially surrounding the crank case connected to said coil and having its ceiling wall in common with the bottom wall of the cooling chamber, the crank case being closed by a wall lying substantially entirely within said receiver.

11. In a refrigerating machine, a vertically extending compression cylinder and a crank case at the lower end thereof, a cooling chamber above the crank case surrounding the top of and substantially the entire side walls of the compression cylinder and having a coil therein connected to the cylinder for cooling a refrigerant, and a liquid refrigerant receiver beneath said chamber connected to said coil substantially surrounding said crank case, said crank case being sealed from said receiver.

12. In a refrigerating machine, a vertically extending compression cylinder and a crank case at the lower end thereof, a cooling chamber above the crank case surrounding the top of and substantially the entire side walls of the compression cylinder and having a coil therein connected to the cylinder for cooling a refrigerant, and a liquid refrigerant receiver beneath said chamber connected to said coil substantially surrounding said crank case, said crank case being sealed from said receiver, the upper end of said crank case having a sealing wall and a piston rod extending therethrough, a piston in said cylinder, a passage leading into said cylinder above said sealing wall below the piston for introducing expanded refrigerant returning to the compressor.

13. In a refrigerating machine, a compression cylinder and a cooling chamber surrounding the cylinder, a coil in said chamber for condensing on its surface refrigerant compressed in said cylinder, a liquid refrigerant receiver having communication with said cylinder, and a crank case connected to said cylinder disposed contiguously to the receiver in position to be cooled by transfer of heat from itself to the receiver.

In witness of the foregoing I affix my signature,

FRENCH E. DENNISON.
